UNITED STATES PATENT OFFICE.

JOSEPH WOOD AND WALTER HAYNES, OF PHILADELPHIA, PENNSYLVANIA.

AUXILIARY SHIFTING GUIDE FOR SPINNING AND ROVING MACHINES.

Application filed May 6, 1924. Serial No. 711,333.

To all whom it may concern:

Be it known that we, JOSEPH WOOD and WALTER HAYNES, citizens of the United States, and subjects of Great Britain, respectively, residing at Philadelphia, in the county of Philadelphia and State of Pennsylvania, have invented new and useful Improvements in an Auxiliary Shifting Guide for Spinning and Roving Machines, of which the following is a specification.

Our invention relates to a new and useful improvement in auxiliary shifting guides for spinning and roving machines, and has for its object to so construct and place a series of the guiding mechanism relative to a spinning or roving machine that it will insure the proper amount of transverse movement to the strand of yarn or thread in its feed to the leather covered drawing rolls, thus preventing the cutting of the leather covering of said rolls and therefore preventing the occurrence of flaws in the strands or threads which has heretofore been a serious drawback to such machines.

With these and other ends in view, this invention consists in the details of construction and combination of elements hereinafter set forth and then specifically designated by the claims.

In order that those skilled in the art to which this invention appertains, may understand how to make and use the same, we will describe its construction in detail, referring by numerals to the accompanying drawings forming a part of this application, in which:

Fig. 1 is a side elevation of a portion of a spinning machine showing our improvement applied thereto.

Fig. 2 is a plan view of Fig. 1, the outer bar of the shifting frame being included.

Fig. 3 is a detail side view of one of the side bars of the shifting frame.

Fig. 4 is an enlarged plan view of one of a number of specially constructed combined bearing and guide bracket.

Fig. 5 is an edge elevation of Fig. 4.

Fig. 6 is a rear view of Fig. 5.

Fig. 7 shows a strand of yarn or fibrous material as it is produced upon a spinning machine having this improvement embodied therein.

In carrying out our invention as here embodied, 1 represents the frame of a spinning machine of usual construction in which

a feed roll 2 coacts with the roll 3 for guiding the yarn or other fibrous material from the supply spool or bobbin, 4 and 5 are the guide or supporting rolls over which the strand of yarn 6 passes and these last named rolls are mounted in open bearings in the brackets 7 which brackets are adjustably mounted upon the frame and held in any adjustment by the bolts 8 and such a machine is also provided with a series of standards 9 in which are journaled the leather covered drawing rolls 10 which coact with the fluted rolls 11 for drawing or elongating the yarn during the process of spinning.

12 represents our combined bearing and guide brackets one of which is adjustably attached to certain of the standards 9 in order that a guide roll 5^a may be journaled in these brackets in close proximity to the drawing roll 10; and 13 represents the open bearing in each of the brackets for the reception of the shaft of the roll 5^a.

Formed with and projecting from the bracket 12 is a guide member 14 in which is formed the slot 15 for the reception of the transverse shifting bar 16 and this bar carries the guides 17 each having a suitable hole therein for the passage of the strand 6 on its way to the rolls 10 and 11. The shifting bar 16 has annular extensions 18 by means of which it is secured to the side bars 19 of the shifting frame and said side bars having upturned slotted ends 20 for the reception of the bolt 21 for securing the parts together.

The side bars 19 are connected with the angular extensions 22 of the shifting bar 23 which is provided in machines of this type, this last named shifting bar also carrying the guides 24 having the usual holes therethrough for the passage of the strands or threads 6. The bars 19 of the shifting frame are slotted as indicated at 25 so that the bolts 26 passing through suitable holes in the extensions 22 and said slot will secure the shifting bar 23 to the frame 19 in such manner that the shifting bar 23 may be adjusted to accomodate the adjustment of the rolls 2 and 3 and the rolls 5 for spinning material of various lengths of fibre. The usual mechanism for reciprocating the shifting bar 23 is utilized for reciprocating the shifting bar 16 since these bars are coupled up as before described by the side bars 19. This reciprocation of the shifting bars 16 and 23 and consequently the guides car-

ried thereby is such as to shift the travel of the strands or threads 6 in their passage to the drawing rolls 10 and 11 so as to cause said threads to travel back and forth laterally between the last named rolls, thus wearing the leather surface of the rolls 10 evenly since the threads in their passage beneath this roll are never permitted to dwell at any point thereby avoiding the tendency to cut or wear grooves in the leather cover.

Heretofore this lateral shifting of the threads has been effected by guides placed at a considerable distance from the rolls 10 and 11 so that the threads were presented at such a slight angle to the rolls as to make the lateral shifting of said threads uncertain with the result that the leather coverings of the rolls 10 in a short time were cut or grooved but we have entirely overcome this difficulty by so constructing the combined bracket 12 that it may be bolted directly against the standards 9 and as these brackets carry the guide members 14 the reciprocating bar 16 and the guides 17 carried thereby are brought in close proximity to the rolls 10 and 11 thus insuring a positive even lateral shifting of the threads 6 between these rolls. This construction and arrangement also leaves the standards 7, rolls 2 and 3 and shifting bar 23 independent for adjustment to accomodate for the spinning of material of different length fibre. By actual practice we have demon-

strated that the producing of faulty work 35 is entirely overcome by the use of our improvement and that perfect threads are spun such as represented in Fig. 7.

Of course we do not wish to be limited to the exact details of construction as herein 40 shown as these may be varied within the limits of the appended claims without departing from the spirit of our invention.

Having thus fully described our invention, what we claim as new and useful is:— 45

1. In a machine of the character described in combination with the bearing standards of the drawing roll, combined bearing and guide brackets secured to said standards, a guiding roll journaled in the 50 brackets, a laterally reciprocating bar mounted upon said brackets, and a series of thread guides mounted upon said bar.

2. In a spinning machine having bearing standards for drawing rolls, a series of combined bearing and guide brackets secured to said standards, a guide roll journaled in said brackets, a reciprocating bar also mounted in said brackets, and a series of 55 thread guides carried by said bar, said guides projecting in close proximity to the drawing rolls and having holes there-through for the passage of the threads being spun.

In testimony whereof, we have hereunto 65 affixed our signatures.

JOSEPH WOOD.
WALTER HAYNES.
